UNITED STATES PATENT OFFICE.

PATRICK J. DERVIN, OF NEW YORK, N. Y.

PIPE-COUPING.

SPECIFICATION forming part of Letters Patent No. 687,917, dated December 3, 1901.

Application filed April 4, 1901. Serial No. 54,248. (No model.)

To all whom it may concern:

Be it known that I, PATRICK J. DERVIN, a citizen of the United States, residing at New York, in the county of New York and State 5 of New York, have invented certain new and useful Improvements in Pipe-Couplings, of which the following is a full and complete specification, such as will enable those skilled in the art to which it appertains to make and 10 use the same.

This invention relates to coupling devices for lead pipes; and the object thereof is to provide improved devices of this class by means of which the ends of lead pipes may 15 be quickly, easily, and securely connected.

The invention is fully disclosed in the following specification, of which the accompanying drawings form a part, in which the separate parts of my improvement are designated 20 by the same reference characters in each of the views, and in which—

Figure 1 is a side view of a lead-pipe coupling made according to my invention; Fig. 2, a longitudinal section thereof; Fig. 3, an end 25 view; Fig. 4, a longitudinal section of one part of the coupling; Figs. 5, 6, 7, 8, and 9, detail views of other parts of the coupling, and Fig. 10 a section of a collar or ring which forms a part of said coupling.

30 In the drawings forming part of this specification I have shown at 5 two lead pipes, and in the practice of my invention I provide a tube 11, having beveled or conical ends 11^a and provided near one end with an annular 35 rib or flange 11^b, and the opposite end of which is screw-threaded, as shown at 11^c, and provided with a screw-threaded collar or ring 11^d, having spanner-holes 11^e, by which it may be screwed onto the tube 11. I also provide 40 metal sleeves 12, one of which is mounted on each of the tubes 5, and these sleeves are larger at their adjacent than at their outer ends to correspond with the beveled or conical ends of the tube 11, and the adjacent 45 ends of said sleeves are screw-threaded, as shown at 12^a, and said sleeves are connected by a central tube or sleeve 13, having a thickened central portion, and the central bore of the ends of which is enlarged, as shown at 50 13^a, whereby annular shoulders 13^b are formed in said sleeve or tube.

In practice the adjacent ends of the lead

tubes 5 are expanded, as shown at 5^a, and this may be done by any suitable instrument, and the beveled or conical ends of the central 55 tube 11 are inserted thereinto. The sleeves 12 are then moved up onto the enlarged portion of said tubes 5, as shown in Fig. 2, and the tube or sleeve is moved on from the right-hand end of the coupling and screwed onto 60 the left-hand sleeve 12, after which the ring or collar 11^d is screwed into position, as shown in said figure, and the right-hand sleeve 12 is then screwed into the end of the sleeve or tube 13. The sleeve or tube 13 may be first 65 placed in position on the tube 11 and the sleeves 12 may be screwed thereinto, and said sleeve or tube 13 and the sleeves 12 are each provided with angular surfaces 14, whereby a wrench may be applied thereto. 70

By means of this construction I provide a coupling for lead pipes whereby the pipes may be securely connected at all times and whereby the coupling will not reduce the strength of the pipes, and it will be apparent 75 that any desired material may be used for the inner tube 11 of the coupling, and a coupling of this class may thus be made to serve for the connection of lead pipes through which acids and other substances of this class are 80 passed.

Having fully described my invention, what I claim as new, and desire to secure by Letters Patent, is—

1. A coupling for lead pipes, consisting of 85 an inner tube, the ends of which are beveled and adapted to be inserted into the ends of the pipes which are correspondingly enlarged, said tube being provided near one end with an annular collar or flange, and near the other 90 end with a detachable collar or ring, an outer sleeve or tube placed on the inner tube and held in place by said collar or ring, and end sleeves which are adapted to be mounted on the tubes and the adjacent ends of which are 95 enlarged, said end sleeves being adapted to be screwed into the ends of the outer tube or sleeve, substantially as shown and described.

2. A coupling for lead pipes, comprising a 100 tube 11 the ends of which are beveled or conical, said tube being provided near one end with a flange 11 and near the opposite end with a detachable screw-threaded collar or

ring 11^a, an outer tube or sleeve 13 mounted on the first-named tube, and provided near each end with inwardly-directed shoulders or projections and sleeves adapted to be mounted on the tubes to be coupled, and the adjacent ends of which are enlarged, said sleeves being adapted to be screwed into the opposite ends of the outer tube or sleeve, substantially as shown and described.

In testimony that I claim the foregoing as to my invention I have signed my name, in presence of the subscribing witnesses, this 1st day of April, 1901.

PATRICK J. DERVIN.
